UNITED STATES PATENT OFFICE.

RICHARD GREENLEAF TURNER, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

UNIFORMLY-TENSIONED LOOM LET-OFF.

Application filed December 30, 1926. Serial No. 158,092.

This invention relates to tension devices for loom let-offs and it is the general object of the invention to provide means whereby the original tension of the warp may be established after a pick-out.

In the weaving of certain fabrics it is highly desirable to preserve the same warp tension throughout the weaving operation and it is also necessary to be able to slacken the warp to permit a pick-out and then to restore the original tension so that the first pick after the pick-out will be layed under the same tension as those picks layed prior to the pick-out. It is an important object of my present invention to accomplish the aforesaid desired result by means of a differential gearing interposed between a friction device and the warp supply coupled with means for moving the system of gearing manually.

It is a further object of my invention to provide a friction head and a warp supply connected together by differential planetary gearing so arranged that when the warp is loose at the time of pick-out the planet gears may be moved manually to move the warp supply while the friction device remains at rest, the increasing tension of the warp being ultimately equal to that of the friction device so that said friction device may turn, thus restoring the warp to its normal tension.

It is a more particular object of my invention to provide a warp delivery drum to be used in conjunction with a creel and having rolls which may be pressed against the drum approximately at the points where the yarn is tangent thereto so as to cause all of the warp threads to lie in a plane to be fed to the drum without cross-overs. A pair of such rolls may be used so as to be effective whether the warp is being moved normally toward cloth forming position or reversely at the time of pick-out.

With these and other objects which will appear as the description proceeds, my invention relates to arrangements and combinations of parts hereinafter set forth, and more particularly pointed out in the claims.

In the accompanying drawings, wherein a convenient embodiment of my invention is shown,

Fig. 1 is an end elevation of a loom having my invention applied thereto,

Fig. 2 is a top plan view of that end of the loom shown in Fig. 1,

Fig. 3 is an enlarged horizontal section on line 3—3 of Fig. 1,

Fig. 4 is a vertical section on line 4—4 of Fig. 3 but showing the parts in substantially the same scale as in Figs. 1 and 2.

Referring to the drawings a loom frame 10 supports warp delivery drum 11 loosely mounted for free rotation on shaft 12 carried by loom bearings 13 one of which is shown in the drawings. The warp W may be drawn from a creel and may be led over fixed guide bar 14 to movable rod 15 and then over fixed rod 16, from which point the warp is taken to the drum. After being wrapped around the major part of the circumference of the drum the warp may be threaded between fixed guide rods 17 and then led forwardly to cloth forming position.

The means for varying the resistance offered to the rotation of the drum includes hand lever 18 pivoted to the loom frame at 19 and extend forwardly to rest on a block 20 through which extends a screw 21. Said screw is mounted in a fixed bracket 22 and the block is held against rotation by engagement with a portion of said bracket extending parallel to the screw. By means of hand wheel 23 said screw may be turned to raise or lower the block and thus vary the vertical position of the hand lever 18. The latter may be flexed over the block to the position indicated in dotted lines in Fig. 2 when it is desired to disconnect said lever from the adjustable securing means. A depending arm 24 on the lever is connected to a rearwardly extending rod 25 which in turn is connected to one arm of bell crank lever 26 and the other arm of which is connected to one end of a flexible friction band 27 as at 28. The other end of said band is fixed with respect to the loom frame as at 29, extending around and in frictional contact with a friction head 30 to be described hereinafter. By varying the position of the hand lever the tension of the band 27 and hence the resistance afforded to the friction head 30 may be varied.

Manual operation of the friction head may be facilitated by means of a shaft 31 having a hand wheel 32 secured to the forward end thereof and a bevel pinion 33 secured

to the rear end thereof, said pinion meshing with a bevel gear 34 secured to shaft 12. The matter thus far described is of common construction with the exception of the manner of supporting the drum and the friction head.

In carrying my invention into effect I provide differential planetary gearing between the friction head 30 and the warp delivery drum 11. Accordingly, I secure an arm 40 to the shaft 12 by means of a key 41 and provide said arm with a stud 42 loosely mounted therein and having on the left end a pinion 43 of relatively small diameter to mesh with the gear 44 bolted or otherwise secured to the web 45 of the friction head 30. A second pinion 46 somewhat larger than the pinion 43 and having more teeth thereon is secured to the other end of the stud 42, said larger pinion meshing with a gear 47 of somewhat smaller pitch diameter than the gear 44 and secured to spider 48 in any approved manner.

Under normal conditions the feeding of the warp W through the loom and around the drum 11 causes the latter to overcome the friction between band 27 and friction head 30. Under these conditions the gearing is moved as a unit about shaft 12, there being no relative movement between the pinions and their gears. At the time of pick-out the hand wheel 32 will be turned to give shaft 12 a reverse movement. At this time friction head 30 will be held against movement by the friction band 27 and as the drum is turning in a reverse direction there is comparatively little strain on the yarn and gear 44 will be at rest with pinion 43 moving around the same. As pinion 43 rotates the larger pinion 46 will also rotate to cause a movement on the part of gear 47. Since the gear 47 is secured to the drum the latter is moved while the friction head is at rest. After the pick-out has been completed and it is desired to restore the original tension, hand wheel 32 will be turned in the reverse direction, the friction head 30 still being held against movement by the band 27. The parts will move in a direction the reverse of that already described so as to take up the slack of the warp W. During this reverse movement the drum will rotate until the fell of the cloth is against the loom reed. This will arrest the reverse movement of the yarn and the friction head will begin to turn, thus putting the warp under the original tension prior to starting up the loom. It is therefore impossible to subject the warp with a pressure greater than that permitted by the friction elements.

From the foregoing it will be seen that I have provided a let-off which permits a restoration of normal warp tension after a pick-out, the device including a system of differential gearing between the friction ele-

ment and the warp delivering means. It will further be seen that the system of gearing can be controlled from the front of the loom so as to vary the warp pressure at will. Furthermore, it will be seen that the friction head and the warp delivery drum are so related that one will usually remain stationary while the other turns during the restoration of the normal tension, i. e., when slack is being taken up the friction head will remain at rest and when the warp drum is tightened to the proper tension the friction band will then move to prevent an increase of pressure.

Referring to Fig. 1 it will be seen that I have provided a pair of rolls held yieldingly against the friction drum substantially at the points where the warp threads are tangent thereto. These devices are substantially similar and I will describe but one of them. A shaft 50 has secured at each end thereof a lever 51 and is provided with an extension 52 to which is secured one end of a spring 53, the other end of which is fastened to the loom frame 54. A fixed stop 55 is positioned for engagement with extension 52 when the levers are thrown in inoperative position. It is to be understood that there are two levers for each shaft 50, one on each side of the loom, and said levers afford supporting means for a pressure roll 56 preferably, though not necessarily, rotatably mounted on the lever 51.

Under normal conditions the spring 53 will lie to one side of the shaft 50 to hold the roll against the warp. When it is desired to alter any of the warp threads the roll may be raised away from the drum until extension 52 engages stop 55, the spring 53 being sufficiently strong to hold the roll elevated, with the axis thereof below shaft 50. In this way I prevent the threads from crossing each other as they are led to the drum, whether the latter be advancing normally or are being reversed.

Having thus described my invention it will be apparent that changes and modifications may be made therein by those skilled in the art without departing from the spirit and scope of the invention, and I do not wish to be limited to the details herein disclosed, but what I claim is:

1. In let-off mechanisms for looms, a warp delivery means, friction means normally effective to resist movement of the warp delivery means, differential gearing interposed between the warp delivery means and the friction means, and means for manually moving the differential gearing to cause a relative movement between the warp delivery means and the friction means.

2. In let-off mechanisms for looms, a warp delivery means, friction means including a movable member, a gear for each of said means, and manually operable planet-

ary gears meshing with the gears for said means, said planetary gears having the same angular movement when moved about either gear.

- 5 3. In let-off mechanisms for looms, a warp delivery means, a friction means normally resisting movement of the warp delivery means, a gear moving with the warp delivery means, another gear of different size from the first named gear moving with the friction means, a pair of connected planetary pinions of different sizes, the smaller pinion meshing with the larger gear and the larger pinion meshing with the smaller gear, and a device to cause said pinions to move in unison about the gears.
- 10 4. In let-off mechanisms for looms, a warp delivery means, a friction means normally resisting movement of the delivery means, and having a rotating member, a gearing unit for the member including a gear secured thereto and a pinion meshing with the gear, a second gearing unit for the warp delivery means having a gear moving with said delivery means and a pinion meshing with the gear therefor, the ratio between the gear and pinion being different for the two units, and means to move the pinions in unison.
- 15 5. In let-off mechanisms for looms, a warp delivery means, a friction means normally resisting movement of the delivery means, and having a rotatable member rotatable about the axis of the warp delivery means, gears of different sizes secured one to each of said means, a pair of pinions of different sizes meshing with the gears and movable as a unit about the axis of the delivery means and member, and means for manually moving said pinions as a unit about said gears.
- 20 6. In let-off mechanisms for looms, a

warp delivery means, a rotatable friction head, means to resist movement of the friction head under normal conditions, two pair of gears, the members of one pair being of different sizes and being one fixed to the delivery means and the other fixed to the friction head, the other pair of gears being of different sizes, the gears of one pair meshing with the gears of the other pair, and manual means for moving one of said pairs around the other while the friction head is held stationary to cause a relative movement of the delivery means.

7. In let-off mechanisms for looms, a warp delivery means, a friction head, a relatively fixed member to resist movement of the head, a gear fixed to the delivery means, another gear of different size fixed to the friction head, a pair of planetary pinions meshing with the gears, and means to move said pinions about the gears to cause movement of the delivery means when the relatively fixed member resists movement of the friction head.

8. In let-off mechanisms for looms, a shaft, warp delivery means loosely mounted on the shaft, a friction head loosely mounted on the shaft, means to resist movement of the friction head, a gear moving with the delivery means, another gear of different size moving with the friction head, planetary pinions of different sizes meshing with the gears and movable together about a common axis, a support secured to said shaft on which the pinions are mounted, and manual means to rotate the shaft when the friction head is held against movement to cause angular movement of the warp delivery means.

In testimony whereof I have hereunto affixed my signature.

RICHARD GREENLEAF TURNER.
